BATH SPRAY

Filed Feb. 21, 1925

UNITED STATES PATENT OFFICE.

JOHN F. NAGORSKI AND OTTO C. CECIL, OF BEDFORD, OHIO.

BATH SPRAY.

Application filed February 21, 1925. Serial No. 10,889.

To all whom it may concern:

Be it known that we, JOHN F. NAGORSKI and OTTO C. CECIL, citizens of the United States, residing at Maple Heights, Bedford, in the county of Cuyahoga and State of Ohio, have invented certain new and useful Improvements in Bath Sprays, of which the following is a specification, reference being had to the accompanying drawings.

10 This invention relates to bath showers, and particularly to that variety of bath shower in which a perforated ring-like member is used from which the water descends.

One of the objects of the present invention is to provide a device of this character which is very simple, which is formed of a plurality of parts readily connectible with or disconnectible from each other, and in which means is provided for keeping an even pressure of water throughout the entire extent of the ring so as to secure an even discharge of water from the ring.

A further object is to provide a ring composed of sections, certain of the sections being interchangeable so that the ring may be made of various sizes, thus permitting large rings to be used for adults and small rings to be used for children, and in this connection provide means for permitting the discharge of water at the points where the sections join each other.

A still further object is to provide a device which either may be used by holding it in the hand above the head or moved 35 opposite any desired portion of the body to cause the discharge of water against the body or which may be placed around the neck and discharged downward over the body.

40 Another object is to provide a device of this character which, when taken apart, will occupy but small space, and may be compactly packed for use by travelers.

Still another object is to so form the 45 perforations in the sectional ring that certain streams will be directed inward from the center of the ring, certain streams directed downward, and other streams downward and inward.

50 Other objects will appear in the course of the following description.

Our invention is illustrated in the accompanying drawing, wherein:—

Figure 1 is an under side plan view of

a bath shower constructed in accordance 55 with our invention;

Figure 2 is a sectional view through the handle, the T, and a portion of the ring;

Figure 3 is a section on the line 3—3 of Figure 2;

Figure 4 is a face view of one of the sections which form the ring;

Figure 5 is a view showing the device in use;

Figure 6 is a like view showing another 65 manner of using the spray.

Referring to this drawing, 10 designates what may be termed the handle of the shower device, which is contracted at one end and formed with a nipple 11 to fit within a flexible hose 12, this hose in turn being provided at one end with means whereby it may be adapted to engage with the ordinary faucet as, for instance, the faucet of a bath tub. That end of the handle 10 75 which is remote from the reduced end 11 is interiorly screw-threaded at 14.

Coacting with the handle member 10 is a T 15, having an exteriorly threaded nipple 16 adapted to engage with the interior 80 threads 14 and having two branches extending in opposite directions from this medially disposed nipple. A wall 17 extends across the junction of one of these branches with the nipple 16 so that the water descending into the T must be directed in one direction as, for instance, toward the right in Figure 2. The extremities of the branches are reduced in diameter at 18 so as to form nipples whose extremities are slightly 85 swelled, and these nipples are provided with longitudinally extending slots 20.

Coacting with the T 15 is a perforated section. We contemplate that a plurality of these perforated sections may be used of 90 different lengths, and we have illustrated two perforated sections 21 and 21^a, the perforated section 21 being shorter than the section 21^a. These sections are formed of rubber hose or other flexible material and the 100 extremities are bent and adapted to slip over the enlarged ends of the nipples 18 so as to form a water-tight joint, as shown in Figure 2. The extremities of the sections 21 and 21^a are perforated, as at 22, and when these 105 sections are placed upon the nipples 18 these perforations will register with the slots 20. The branches of the T 15 have preferably

three longitudinally extending rows of perforations 23 and the sections 21 or 21^a also have three longitudinally extending rows of perforations 23. These perforations are so arranged that one row of perforations discharges water directly downward and the other row of perforations discharges water downwardly and centrally of the ring and the other row of perforations discharges water centrally entirely. Thus the water will be directed toward the body in a variety of directions and the last named and next to the last named perforations will discharge streams which will meet at one point, (see Figure 3).

This device, it will be seen, may be used as illustrated, that is, with the ring disposed around the neck of the user and the stream discharging inward toward the neck, downwardly and centrally and directly downward. The handle 10 is of sufficient length so it will support the hose 12 some little distance away from the body, thus permitting the body to be thoroughly washed and rubbed beneath the point where the hose extends downward. It will further be seen that any sized ring section 21 or 21^a may be used so as to fit the device for use either with small children or for adults. Furthermore, it will be obvious that in place of putting the device around the neck, it may be held just in the hand and used as a spray and discharge either downwardly against the head or against the body as desired. The slots 20 with the corresponding holes in the ends of the sections 21 or 21^a will permit the discharge of water at the junction of the sections 21 or 21^a with the branches of the T 15. Inasmuch as the device is made in sections, it is compact and may be readily placed within a valise, bag or trunk. The device is very simple, can be readily detached from or attached to any spigot, and has been found particularly effective in practice.

While we have illustrated certain details of construction, we do not wish to be limited thereto as it is obvious that changes might

be made without departing from the spirit of the invention as defined in the appended claims.

50

We claim:—

1. A bath spray of the character described comprising a handle adapted at one end for connection to a flexible hose, the opposite end of the handle being provided with a T, 55 the T at the extremities of its branches being formed to provide nipples, the nipples being longitudinally slotted, and a flexible section adapted at its ends to be engaged with said nipples and formed at its ends 60 with holes registering with the slots in the nipples, the inner face of the T and the inner face of the flexible section being provided with longitudinally extending rows 65 of perforations.

2. A bath spray of the character described comprising a handle having a reduced extremity at one end and a screw-threaded extremity at the other, a hose detachably connected to the first named extremity and adapted to be connected to a faucet, a T having a screw-threaded portion engaging the screw-threaded end of the handle, the T being formed with two slightly curved, laterally projecting branches terminating in longitudinally slotted nipples and there being a partition wall within the T disposed at the junction of one of said branches with the body of the T and directing water entirely into one of said branches, 75 and a flexible section adapted to be curved into the form of a partial ring and having its ends engageable with the nipples on the ends of the branches, the ends of the flexible sections having perforations adapted to register with the slots in the nipples, the inner face of the T and the inner face of the flexible section being formed with a plurality 80 of rows of perforations.

In testimony whereof we hereunto affix 85 our signatures.

JOHN F. NAGORSKI.
OTTO C. CECIL.
